UNITED STATES PATENT OFFICE

WALTER C. TROUT, OF LUFKIN, TEXAS

PUMPING UNIT

Application filed December 15, 1930. Serial No. 502,407.

The invention relates to an improvement in pumping units of the type generally used in connection with recovering oil or water from wells.

Various types of pumping units have been placed in commercial use heretofore and have embodied a power unit and crank assembly. This unit would be mounted on a permanent foundation such as concrete and used in connection with the Samson post and walking beam which were mounted on the derrick foundation. Such devices, however, have been found in many instances to be unsuitable as the Samson post and the walking beam are mounted on one foundation and the pumping unit on a separate foundation and unless the expense and forethought were resorted to in order to provide a suitable foundation for both portions of the pumping apparatus at the time the derrick was built, considerable additional expense and inconvenience were generally encountered. Great difficulty was also encountered in properly aligning the foundations where they were embodied separately and various other difficulties directly traceable to this setup of conditions were encountered.

The present unit has been devised with the idea in mind of providing a mechanism as a unitary structure mounted on a frame work or skids so that it might be readily transported from place to place and disposed on the derrick foundation or drilling platform and still have the assurance that all of the parts would be in proper alignment and in position to accomplish their function.

It is one of the objects of the invention to provide a simple and economical pumping unit which embodies a source of power, crank, pitman, walking beam, Samson post and supporting structure, all assembled and capable of transportation as a unit.

Another one of the objects is to devise a composite portable pumping or drilling unit which may be disposed on the well derrick floor.

Another object of the invention is to provide a pumping unit including a driving mechanism, crank, pitman, walking beam and Samson post so arranged with respect to

each other that they may be mounted upon skids and located on the derrick floor of a well drilling rig.

Another object of the invention is to provide a pumping unit having a counterbalance mechanism disposed on each end of the crank shaft.

It is also an object of the invention to provide a pitman for pumping unit which is adapted for connection to crank arms disposed in opposite ends of the crank shaft.

Still another object of the invention is to provide a pitman having a yoke formation so that it may be connected to two wrist pins.

It is also an object of the invention to provide a walking beam having a saddle extending beyond and connected to the underside of the beam.

A still further object of the invention is to provide a counter balance mechanism for both ends of the crank shaft in connection with an oil well pumping unit.

It is also intended to provide a novel bearing structure for connecting a yoke shaft pitman to the walking beam.

Other and further objects of the invention will be readily apparent to those skilled in the art to which the invention appertains when the following description is considered with the accompanying drawings wherein:

Fig. 1 is a side elevation of a complete assembly of the improved pumping unit.

Fig. 2 is a sectional view taken on the line 2-2 of Fig. 3 and showing the internal construction of the pitman connection with the walking beam.

Fig. 3 is an end elevation of the pumping unit looking from the left hand side of Fig. 1 with the Samson post omitted.

Fig. 4 is an end elevation of the structure looking from the right hand side of Fig. 1.

The present pumping unit is particularly adapted for congested drilling conditions where the derrick or other structures do not permit of distribution of the parts over a considerable area and also adapts itself for conditions where the derrick is disposed over bodies of water or marshy land. Where the derrick must be erected upon piling, and a pumping unit of the type now in general use

use is to be employed, it is necessary to erect an additional foundation for the pumping unit but with the unit disclosed in this application it is intended that no additional foundation need be erected as the unit may be disposed upon the derrick floor and is so balanced due to the provision of the double counter weight structure that vibration is practically eliminated.

10 By having reference to Fig. 1, a supporting structure is indicated at 2 and may include suitable structural shapes such as I beams or channel constructions which may be used as skids or base members and upon which the mechanism may be assembled. The supports are seen in end elevation in Figures 3 and 4 and may be cross braced by means of the member or members 3. The ends of the supports 2 have been inclined 20 upwardly at 4 so that they may be skidded about and pass over obstructions. Additional cross bracing 5 may be provided on the upper flanges of the members so that they will form a frame work to support the Samson post 7, the power unit 8, the gear unit 9 and counterbalances 10. The Samson post 7 is shown as connected to the supporting structure by means of plates 12 which may be bolted or otherwise fastened to the support.

25 The Sampson post includes a triangular frame member having the braces 13 and 14 on one side and the central brace member 15 on the opposite side. These braces converge and are received by the saddle 16 which supports the center iron 17. On the center iron 17 is mounted the walking beam 18 which is adapted for reciprocation by means of the pitman 19. The end of the walking beam opposite from the pitman receives a temper screw or bridle 20 which is adapted for connection to a cable for the standard method of drilling or to a string of sucker rods for pumping.

30 40 The gear unit 9 may be of any desired construction and embodies speed reducing gears or the herring bone gears which are now in general use. These gears reduce the speed of the operating motor 8 which drives the belt 21 connected to the drive wheel 22. This drive wheel is mounted on a shaft 23 which drives the gears inside of the unit. The last gear of this train is connected to the crank shaft 24 which carries the cranks 25. As seen 45 in Figures 3 and 4, there are two cranks 25, one mounted on each end of the crank shaft which projects from the gear unit 9. It is believed that this is a novel construction in a pumping unit of the present type and is of 50 particular advantage in a small unit because it eliminates whipping of the crank shaft and vibration of the entire unit.

55 The particular structure of the cranks 25 is not important to the practicing of the present invention but they may be of the type

shown in my prior Patent 1,588,784 granted June 15, 1926 but I do not desire to be limited to this particular type of the counterbalance as any type in which the weights are adjustable to balance the well may be employed.

70

With the counterbalance here illustrated, however, the weight members 26 are attached to the crank 25 by means of bolts 27 and are confined in the slots 28 so that the weight may be moved longitudinally of the crank 25 to 75 adjust its counterbalancing or balancing effect upon the weight of the rods and fluid column in the well.

75

80 The cranks 25 are provided with a plurality of openings 28, each of which is adapted to receive the crank or wrist pin 29, to which the pitman 19 is to be connected. The particular opening 28 in which the pin 29 is to be disposed is governed by the length of the stroke which is to be made in the pumping or 85 drilling operation. The pitman 19 is connected to the crank pin 29 by means of a releasable bearing 30.

85

90 The pitman 19 is of a special construction in order that it may straddle the gear unit and cranks and be connected on opposite sides and in this manner balance the entire unit. As seen in Figures 3 and 4, the pitman includes an inverted U-shaped rod portion 35 provided with a cross brace 36 and having one of the 95 bearing or rod clamps 30 connected at each end. With this arrangement it will be readily apparent that the entire unit may be symmetrically disposed with respect to the walking beam 18 which will thus oscillate in the 100 plane along the center line of the pumping unit. This is of material advantage as the unit may be located directly beneath the walking beam instead of to one side as is now the general practice. With the stresses occurring 105 symmetrically with respect to the pumping unit, the load may be readily balanced and enormous economies effected in production of the unit due to the fact that the various parts thereof may be constructed of much 110 lesser weight and strength as they are not subjected to vibration and strains which have heretofore been encountered.

100

110 The pitman 19 is connected to the walking beam as best seen in Figs. 1 and 3 by means 115 of a bracket 40 which is suitably connected to the walking beam 18 and is here illustrated as including the flanges 41 and 42 which embrace the end of the walking beam in order 120 to insure a rigid connection. Angle plates 43 are fastened to the web 44 of the walking beam in order to receive the flange 42. This bracket 40 has an outward and downwardly 125 extending arm 45 which is formed with a socket 46 in order to receive the ball member 47 which is carried by the pitman rod 35. This ball member is shown in section in Fig. 2 and includes the ball 48, stem 49 and the yoke 50. The ball 48 is received in the socket 46 of the arm 45 and is retained in position 130

by a pair of clamping plates 51 which are connected to the arm 45 by means of the bolts 52. These clamping plates are adapted to straddle the stem 49 so that the ball 48 will be securely held in socket 46 but will be free for limited oscillation in the socket. The yoke 50 embraces the rod 35 and is welded or otherwise attached thereto so that the rod will be firmly connected to the ball member so that the forces 10 may be transmitted from the walking beam 18 to the crank 25.

Obviously the connection between the ball 48 and the socket 46 will require considerable lubrication and for this purpose a valve 55 15 has been provided on the rod or pipe 35 and may be of any standard type in order that lubricant may be injected. A small conduit 56 has been provided across the inside of the pipe 35 so that the lubricant will be discharged at the point 57 inside of the hollow 20 stem 49. The hollow ball 48 forms a chamber 58 which may act as a reservoir for lubricant so that it may pass through the opening 49 to lubricate the surfaces between the ball 25 48 and the socket 46.

Figure 3 shows the yoke 50 as being elongated so that it will embrace a considerable portion of the rod or pipe 35 and insure a steady construction. 30 The temper screw or bridle 20 is shown as attached to the walking beam 18 by an apron 61 which is similar to the construction shown in my co-pending application, Serial No. 492,736, filed November 1, 1930.

35 It is intended in the further development of the invention that various changes and alterations may be resorted to in order to adapt the pumping unit to peculiar conditions arising in actual practice. Broadly the invention contemplates the assembly of all of 40 the structure necessary to perform the pumping or drilling operation upon a unitary frame work, which may be disposed on the derrick floor, and which may be moved from 45 place to place without dismantling the parts.

Having described the invention, what I claim is:

1. A pumping unit for use with a well rig 50 pumping equipment, said unit including a housing, a crank shaft extending from opposite sides thereof, a counter-balanced crank arm on each end of said shaft, and a pitman straddling said pumping unit with opposite sides of its lower end attached to each of said 55 arms, and having its upper end adapted for connection to the well rig pumping equipment.

2. A pumping unit including a housing, a crank shaft extending from opposite sides 60 thereof, a counter-balanced crank arm on each end of said shaft, and a unitary yoke-shaped pitman having its ends connected to said crank arms.

3. An assembly of the character described 65 including an inverted U-shaped pitman, a

walking beam connected to the top of said pitman, and a crank shaft connected to each of the ends of said pitman.

4. In a pumping unit a yoke-shaped pitman, a walking beam, and a bearing connecting said pitman and beam including a ball, a stem thereon, said stem being affixed to said pitman yoke. 70

5. In a pumping unit a yoke-shaped pitman, a walking beam, and a bearing connecting said pitman and beam including a ball, a stem thereon, said stem being affixed to said pitman yoke, and means on said pitman to lubricate said bearing. 75

6. In combination with a double crank arm, 80 pumping unit a walking beam, an arm connected therewith, a pitman rod straddling said arm and connected to the crank arms, and bearing means between said arm and rod. 85

7. A pumping unit balanced to eliminate vibration and including a driving unit, a crank arm on each side thereof, a walking beam centrally disposed with respect to said unit, a single pitman connecting both crank 90 arms to said walking beam, and a swivel bearing forming such connection whereby inequalities of adjustment may be absorbed.

In testimony whereof I hereunto affix my signature this 10th day of December, A. D. 95 1930.

WALTER C. TROUT.
